UNITED STATES PATENT OFFICE.

JAMES MARSHALL LEAVER, JR., OF SONORA, CALIFORNIA.

GAGE.

957,782.

Specification of Letters Patent. Patented May 10, 1910.

Application filed January 15, 1908. Serial No. 410,983.

To all whom it may concern:

Be it known that I, JAMES M. LEAVER, Jr., a citizen of the United States, residing at Sonora, in the county of Tuolumne and 5 State of California, have invented a new and useful Gage, of which the following is a specification.

The present application is in the nature of a division of co-pending application, Serial 10 No. 410,980 filed simultaneously herewith. No broad claims are made in this application to the particular type of structure, inasmuch as said claims are contained in the application above identified.

15 The primary object of the present invention is to provide novel and simple means for permitting the ready adjustment of gage stops upon their supports, without the necessity of completely dismembering the structures, the stops being independently detachable and attachable and having means for preventing their accidental displacement from the support.

25 A further and important object is to provide securing means that also yieldingly holds the stops in active relation, thus permitting their movement to an inoperative position by the material that is being gaged.

In the drawings:—Figure 1 is a view in 30 elevation of a portion of a saw table, showing the improved stop in place thereon. Fig. 2 is a top plan view of the same. Fig. 3 is a detail sectional view on an enlarged 35 scale through the gage. Fig. 4 is a detail view partially in section showing the parts of one of the gage stops. Fig. 5 is a detail perspective view of a portion of the supporting structure. Fig. 6 is a view similar to Fig. 3, but illustrating a modified form of 40 construction. Fig. 7 shows the structure illustrated in Fig. 3 with one of the elements removed. Fig. 8 is a cross sectional view through another embodiment of the invention. Fig. 9 is a view similar to Fig. 8, 45 but showing the holding latch swung to an inoperative position. Fig. 10 is a side elevation of the structure shown in Fig. 8. Figs. 11 and 12 illustrate another embodiment of the invention, with the retaining 50 means respectively in inoperative and operative positions.

Similar reference numerals designate corresponding parts in all the figures of the drawings.

55 Referring first to the embodiment dis-

closed in Figs. 1-4 inclusive, the saw table 13 may be of any desired character, and the saw 14 coöperating with said table, may be of any suitable type. Mounted on the table is a supporting structure comprising a base 60 15 have an upstanding flange 16. The base and flange are slotted, as illustrated at 17, and these slots terminate short of the upper edge of the flange, forming a transverse pivot support 18. The gage stops 19 65 are in the form of flat plates, which operate in the slots 17, and are provided at their upper ends with open sided seats or slots 19^a that receive the pivot 18, said gage stops thus swinging on the pivot. Each open side 70 is normally closed by the curved portion 20 of an arm 21 that is pivoted, as illustrated at 22 to the upper end of the gage stop, and has its lower end weighted, as illustrated at 23. The arm, as shown in Fig. 75 3, is offset from the gage stop, and thus the weight not only serves to maintain the seat 19 closed, but also serves to yieldingly maintain the gage stop in the angle formed by the base 15 and flange 16. With this structure, it will be evident that any gage stop 80 may be removed from or attached to any portion of the pivot support, and when in position, the open side of the seat for the pivot is closed, the weighted arm therefore 85 constituting not only a closure, but means for holding the stop in active position.

A modified form of construction is illustrated in Figs. 6 and 7. In this embodiment, the base 24, has an upstanding flange 90 25. The said base and flange are slotted, as illustrated at 26. Each of the gage stops 27 is provided in its upper portion with an open sided seat or slot, the inner portion 28 of which is enlarged, a 95 contracted open mouth 29 being formed. This mouth is held by the upper end 30 of an arm 31 having a weight 32 at its lower end. The portion 30 of said arm is maintained in the mouth 29 by a suitable screw 100 or other fastener 33. It will be evident that in this structure, the weighted arm 31 not only constitutes a closure for the mouth 29, but also acts as a means for yieldingly maintaining the stop in its active position. 105

A simpler form of the invention is shown in Figs. 8, 9 and 10. In this embodiment, the pivot support, is designated 34, and is provided with spaced collars 35, between 110 which the gage stops 36 are placed. Each

gage stop has an open sided seat or slot 37 that receives the pivot 34, and the open mouth 38 of said slot is normally closed by a latch 39 having a weighted upper end 40, 5 said latch being pivoted upon the gage stop, as shown at 41.

Still another embodiment is disclosed in Figs. 11 and 12. In this form of construction, the pivot is designated 42 and the gage 10 stop 43 has an open sided seat or slot 44 that receives the same. A closure, in the form of a block 43 is arranged to be slipped into the open end of the slot or seat 44, and is provided with connecting tongues 46 engaging in sockets 47 formed in the opposite sides of the slot. When the block is in position, it constitutes a closure for the open end of the slot or seat, the tongues engaging in the sockets 47. In this connection, it is 15 to be noted that the block 45 has recesses to permit the tongues 46 to pass into the slot 44 and spring into the sockets 47.

From the foregoing, it is thought that the construction operation and many advantages of the herein described invention will 20 be apparent to those skilled in the art, and it will be understood that various changes in the size, shape, proportion and minor details of construction may be resorted to 25 without departing from the spirit or sacrificing any of the advantages of the invention.

Having thus fully described my invention, what I claim as new, and desire to secure by Letters Patent, is:—

1. In a gage of the character set forth, the combination with a fixed pivot support, of a gage stop having an open ended seat to receive the same and thereby supported for oscillatory movement and presented in projecting relation with the work, and means pivotally mounted on the gage stop for closing the seat to retain the stop on the pivot support.
2. In a gage of the character set forth, the combination with a fixed pivot support having its cross section presenting two unequal diameters, of a gage stop having a seat of a size to receive the greatest diameter of the 40 pivot and provided with a contracted open mouth, a closure for the mouth mounted on the gage stop and having a weighted arm, said mouth permitting the removal of the 45

stop from the pivot support transversely thereof by the removal of the closure.

3. In a gage of the character set forth, the combination with a pivot support, of a gage stop pivotally and detachably mounted thereon, and common means for preventing the detachment of the stop and for yieldingly maintaining it in a predetermined position.

4. In a gage of the character set forth, the combination with a pivot support, of a gage stop having an open ended seat that pivotally receives the support, and a weighted arm that closes the open end of the seat and yieldingly maintains the stop in a predetermined position.

5. In a gage of the character set forth, the combination with a base, of a pivot support associated therewith said base having a slot, of a gage stop pivotally mounted on the support and having an open ended seat that receives the pivot support, the free portion 75 of said stop operating in the slot, and a weighted arm pivoted to the gage stop and closing the open side of the seat, said arm being offset from the gage stop.

6. In a gage of the character set forth, the combination of a base provided with a slot and supporting a pivot, a stop mounted on the pivot and movable in the slot and held thereby from lateral movement and having an open-ended seat to receive the pivot, and 85 weighted means for closing the seat and permitting a pivotal movement of the stop.

7. In a gage of the character set forth, the combination of a base provided with a slot and supporting a pivot, a stop mounted on 90 the pivot and movable in the slot and held thereby from lateral movement and having an open-ended seat to receive the pivot, and means for closing the seat, said means permitting a pivotal movement of the stop and 95 including a weighted arm or member for maintaining the stop in a projecting position with relation to the support.

In testimony, that I claim the foregoing as my own, I have hereto affixed my signature in the presence of two witnesses.

JAMES MARSHALL LEAVER, JR.
